UNITED STATES PATENT OFFICE.

ALBERT J. GRANBERG, OF SAN FRANCISCO, CALIFORNIA.

DESIGN FOR AN AUTOMOBILE-BODY.

54,615.

Specification for Design.

Patented Mar. 9, 1920.

Application filed September 8, 1919. Serial No. 322,563. Term of patent 7 years.

To all whom it may concern:

Be it known that I, ALBERT J. GRANBERG, a citizen of the United States, and a resident of the city and county of San Francisco, State of California, have invented a new, original, and ornamental Design for an Automobile-Body, of which the following is a specification, reference being had to the accompanying drawing, forming part thereof, in which—

Figure 1 is a side elevation of an automobile illustrating my new design.

Fig. 2 is a similar view of an automobile, parts thereof being broken away to illustrate more clearly the design of the forward portion of the body.

I claim:

The ornamental design for an automobile body, substantially as shown.

ALBERT J. GRANBERG.
